UNITED STATES PATENT OFFICE.

DOUGLAS A. WILSON, OF PEORIA, ILLINOIS, ASSIGNOR TO ROWE MANUFACTURING COMPANY, OF GALESBURG, ILLINOIS, A CORPORATION OF ILLINOIS.

FENCE-MAKING MACHINE.

Application filed December 20, 1926. Serial No. 155,817.

This invention has reference to a fence making machine and particularly to machines designed for the manufacture of "slat fencing". Fencing of the type referred to is made up of a plurality or series of longitudinally spaced cable strands forming the line wires of the fencing and connected by wood pickets or slats. Such fencing is useful for snow fences along railroad right-of-ways and highways; for corn cribbing and like uses, and for yard fences. In most, if not all cases, fencing made of this character has included wood pickets of substantially the same height or length throughout.

The principal object of the present invention is to provide a machine for the manufacture of a slat or wood picket fence, wherein such a fence is ornamental in character and thus may be used for fencing lawns, residential property and estates. Such fencing, therefore, instead of comprising slats or wood pickets of substantially the same height or length throughout, comprises preferably slats which are alternately long and short and their upper or top ends made of corresponding ornamental shapes. Such a structure not only presents a fence of ornamental design which may be used as fencing for the purposes stated, but also provides a fencing with a close spacing at the bottom or lower portion, which close spacing is desirable and which may be more or less open at the top or upper portion of the fence and somewhat reduces the cost in manufacture.

The invention has for a further object to provide a slat or wood picket fence machine including twisting means; means for feeding slats or wood pickets transversely of and to said twisting means; means for placing the slats or wood pickets in position to be engaged and fed by said feeding means to the twisting means, and combined or associated with the twisting, feeding and placing means, means adapted to periodically and successively engage the top cable strand between successive long slats and in line with alternate short slats, whereby a proper twisting of the top cable strand may be effected at the same time as the remaining cable strands of the fence are operated

upon to secure the alternate short slats in position.

A further object of the invention is a packer mechanism for placing the slats or wood pickets into crotches in the line wires formed by the twisting of the strands comprising the same, which said packer mechanism operates in timed relation to the means adapted to periodically engage the top strand during the placing of the alternate short slats or wood pickets.

The invention further comprises structural and operating parts which will more fully appear in the following description.

That the invention may be more fully understood, reference is had to the accompanying drawings forming a part of the description, illustrating a preferred embodiment of the invention, wherein

Figure 1 is a top plan view of a machine embodying my invention, slats or wood pickets being shown in dotted lines in position at the intake side of the machine where they are fed to the twisting mechanism, and slats also being shown in dotted lines at the outgoing side of the machine in the relation they assume with respect to each other and the line wires when the fence is complete;

Figure 2 is a partial front elevation of the machine to show the feeding means for feeding the slats or wood pickets to the twisters.

Figure 3 is an elevation partly in section on the same scale as shown in Figure 2, and as the same would appear if taken on the line 3-3, Figure 1.

Figure 4 is an enlarged vertical sectional view, as the same would appear if taken on the line 4-4, Figure 1.

Figure 5 is an enlarged partial plan view of the parts as they would appear in plan on Figure 4.

Figure 6 is a detail sectional view, as the same would appear if taken on the line 6-6, Figure 5.

Figures 7 and 8 show in elevation the details of the mechanism adapted to periodically and successively engage the top cable strand whereby the proper twisting thereof may be effected when the alternate short slats or wood pickets are woven into the machine; Figure 7 showing by dotted and

full lines the position of the wire engaging or retention member during the twisting of the top strand, and Figure 8 shows the same parts in non-engaging position.

5 Figure 9 is a detail in elevation partly in section of the packer and operating means therefor, the dotted line showing the advanced position of the packer and the relative spacing positions of the slats or wood pickets.

10 Figures 10 and 11 show in detail the successive positions of the retention member adapted to engage and disengage with the top cable strand during the placing of the 15 alternate long and short slats or wood pickets.

15 Figure 12 is a detail perspective view of the retention member which is adapted to engage with the top cable strand and effect the proper twisting of such strand during the placing of the alternate short slats or wood pickets.

20 Figure 13 is a detail plan showing the upper or ornamental portion of the fence and the manner and form of the twists in the cable strand wires, including the top and next adjacent cable strands, and

25 Figure 14 shows a section of fence including a series of the long and short slats or wood pickets and the points of connection by the strands which are here merely indicated by a dotted line.

30 Like characters of reference denote corresponding parts throughout the figures.

35 I desire to state at the outset that I am aware that it is not broadly new to provide a machine for the manufacture of fencing comprising spaced line wires made of cable strands and to connect these strands by slats

40 or wood pickets, as such a fence is not only old in the art, but machines for the manufacture of such fencing are also old in the art, including wire twisters and means for operating the same; slat or wood picket

45 feeding means including what have been referred to as starting and feeding rollers and also a carrier or conveyor for placing the slats or wood pickets in position to be engaged by the starting rollers and fed by the

50 feeding rollers to the twisters, the latter being operated by means of a reciprocating rack bar for rotating the twisters first in one direction and then in an opposite direction, and means being provided for placing the

55 slats or wood pickets into the crotches formed by the twisting of the wires comprising the cable strands. As I have said, there is nothing broadly new in a machine comprising in its makeup the various mechanisms which I have referred to, and whether the machine operates continuously or intermittently is immaterial. I am not aware, however, that automatic machines of this

60 character have ever been made embodying structure included within the invention

herein disclosed for making preferably an ornamental slat or wood picket fence comprising alternate long and short slats or wood pickets, the top or upper ends of which are preferably ornamented.

70 In the drawings, particularly Fig. 1, the means for placing the slats or wood pickets in position to be engaged by the starting rollers and then fed to the twisters by means of feeding rollers, comprises a carrier A, including the spaced endless chains or belts a, which at their forward ends are engaged by sprocket wheels a' on a shaft 5 and at their rear ends the said chains are engaged by sprocket wheels a² on a shaft a³. The manner of imparting power to the said chains or belts a is by means of a sprocket wheel a⁴ on one end of the shaft 5, which is engaged by a sprocket chain a⁵ also engaged by a sprocket pinion a⁶ on one end of an operating shaft 4 which derives its power from the driving shaft 1 in a manner which will be explained. In accordance with the general plan of the machine, the carrier A is located at what may be termed the intake 75 side of the machine and where the slats or wood pickets are shown on the carrier is approximately at the point where the attendant will stand to assort the slats or wood pickets into the assembly, also shown, whereby they may be successively carried into position to be engaged by the starting rollers and thence fed by the feeding rollers to the twisting mechanism. The slats or wood pickets at the far end of the carrier A may 80 be laid thereon by an attendant and gradually fed to the position of assembly, as indicated.

85 The starting rollers B and B', see Figures 1 and 2, are arranged in superimposed relation and normally in non-slat or wood picket engaging position whereby the slats or wood pickets may be inserted therebetween and then operate to engage such slats to feed the same to the feeding rollers C and C', which 90 in turn feed the slats to the twisting mechanism. The feeding rollers C and C' have a preferably fixed relation and their peripheries serrated, toothed or milled whereby they may firmly grip the slats or wood 95 pickets as they are received from the starting rollers, to insure delivery to the twisting mechanism. The peripheral face of the starting roller B is also preferably serrated, toothed or milled, as are the rollers C and C', 100 but the roller B' may be smooth faced, as shown. The feeding rollers C and C' are both positively driven, whereas the starting roller B is the only roller of the two starting rollers which is positively driven, the roller 105 B' being supported so as to be moved in predetermined intervals into frictional engagement with the slats or wood pickets placed between the rollers B and B', to start 110 and cause the same to be engaged by the 115

feeding rollers C and C', whereby the said slats are fed to the twisting mechanism.

2 is an operating shaft receiving its power from the driving shaft 1 through intermeshing bevel gears 6 and 7, respectively, and said shaft 2, through bevel gears 8 and 9, respectively, imparts rotation to the shaft carrying the starting roller B, and said shaft 2, through bevel gearing 10 and 11, imparts rotation to a shaft 12 to which is connected the feed roller C and said shaft 12 also imparts motion to gearing 13 and 14, see Figure 3, through which is imparted motion to a shaft 15 and to the feeding roller C' carried thereby.

3 designates an operating shaft, see Figures 2 and 3, to which is connected a large gear wheel 16 and meshing with said gear wheel is a gear pinion 17 preferably loose on the drive shaft 1 and adapted in a manner to be described, to be clutched and declutched therewith. On said shaft 3, see Figure 2, is a double faced cam 18 adapted during each revolution of the shaft 3 to actuate a lever 19 pivoted at 20 and said lever has a preferable compression spring connection with a bell crank lever 21 pivoted at 22, the latter lever having journaled thereon the preferably smooth faced starting roller B'.

30 The timing of the cam 18 in its relation to the positioning of the twisters to be described, is such that the roller B' is brought into frictional engagement with a slat or wood picket and to force it against the roller B which is being continuously rotated, thus starting the slat in direction of feeding to be engaged by the continuously operated feeding rollers C and C', which feed the same transversely of the line wires and in position 40 with the twisters to be engaged by the packer.

The twister mechanism, which is best shown in its general arrangement in Figure 1 and in detail in certain of the remaining views of the figures, comprises preferably a plurality of twisting spindles or shafts 23 arranged in suitable spaced relation. In this instance there are shown five twisting spindles or shafts, but no limitation is placed 50 on the number, as there may be as many line wires in the fence as may be desirable or occasion may require and they may be placed equi-distantly, or not, as may be desired. Each of these spindles or shafts 23 carries a slotted twister head which is not unlike twister heads which have long been used in machines of this type, in fact the twister heads and spindles in their construction and general arrangement are not unlike 55 those heretofore used, there being one exception and that is in the manner and form of operating the first twister spindle or shaft 23 through which and by means of which the strand wires forming the cable or line 60 wires for the top of the fence are twisted about each other for the purpose of securing the upper ends of the longer slats or wood pickets thereto. Each of the twister spindles or shafts 23, with the exception of the twister for the top marginal cable strand, 70 has connected thereto or is provided with a gear pinion 25, best seen in Figures 3 and 5 and these pinions are engaged by a rack bar 26 adapted to be reciprocated back and forth for the purpose of imparting alternate rotation first in one direction and then in an opposite direction to the spindles or shafts 23. This rack bar has connected thereto a casting 27, see Figures 1, 2 and 3, to which is pivotally connected a reciprocating bar or 75 rod 28, which at its opposite end has a pivotal connection with a lever bar 29 pivotally connected to the frame of the machine at 30 and to said lever bar between its ends is pivotally connected at 31 a slidable frame 32 80 which is slotted at 33 to straddle and have movement transversely of the operating shaft 3, see Figure 3. This frame 32 includes a housing 34 in which rotates an eccentric 35 carried on or secured to the shaft 3; said eccentric adapted to have an alternate and rolling engagement relation with rollers 36 journaled within the housing 34 and so positioned in relation to a horizontal line passing 85 through the axis of the shaft 3, that one roller 36 is above the axis at one side and the other below the axis at the other side of said shaft, as best seen in Figure 3, whereby as the eccentric 35 is rotated with the shaft 3, said eccentric will have a rolling engagement 90 with the rollers 36 to impart reciprocal movement to the frame 32 transversely of the shaft 3, first in one direction and then in an opposite direction, thereby imparting oscillatory movement to the lever arm 29 and 100 reciprocal movement, back and forth, to the bar or rod 28 and in turn the rack bar 26 which imparts alternate rotary movement to the twister spindles or shafts 23.

The marginal spindle 23 for the upper cable strand of the fence is rotated indirectly from the rack bar 26 instead of directly through the pinions 25, as in the case of the other twister spindles. In this instance a short shaft 37 is provided, see Figures 3, 5 and 6, and particularly the latter, to which is secured a gear pinion 38 in meshing relation with the rack bar 26 and also secured to said short shaft 37 is a somewhat larger gear wheel 39 in meshing relation 115 with a smaller gear pinion 40 on the marginal spindle 23. In this arrangement the speed ration of the gearing between the rack bar and the marginal twister spindle and between the rack bar and the remaining twister spindles, is preferably such that the marginal twister spindle for the upper marginal wire of the fence will rotate approximately five times in one direction and approximately five times in the opposite direction.

rection with each reciprocating movement of the rack bar, whereas the other twister spindles will rotate approximately two and one-half turns in one direction and two and one-half turns in the opposite direction with each reciprocation of the rack bar, and in any event the resulting operation or rotation of all of these twister spindles is to bring them into slat or wood picket receiving position simultaneously for the reception of such slats or wood pickets as they are fed across the machine by the starting and feeding rollers.

The slats or wood pickets, as previously mentioned, are fed alternately first a long slat and then a short slat and as they are projected along the machine and through the twisters by means of the starting and feeding rollers, they abut at their lower ends with the stop or frame member 41, see Figure 1. The timing arrangement for the top marginal twister and the remaining twisters, as just previously explained, is to produce the twisting operation of the cable strands forming the longitudinal wires of the fence, as best seen in Figures 10, 11 and 13, it being observed from an examination of the last mentioned figure, that there are short, alternate reverse twisted portions of these cable strands between the adjacent long and short slats or wood pickets, and the marginal wires engaging and holding the upper ends of the long slats or wood pickets and therebetween are twisted in reverse directions from points midway between said long slats or wood pickets and in a manner which I will now explain.

From an examination of Figures 10 and 11 it will be observed how each pair of line wires to form the cable strands are directed through the twister heads 24 for the reception of the long and short slats or wood pickets, and how such wires are twisted into cables between the long and short slats to produce the alternate reverse twisted portions between such long and short slats, as shown in Figure 13, and thereby secure the same in position, and how the top marginal cable is formed to produce the reverse twisted portions between the upper ends of the long slats from and at a point mediate the long slats and in axial alinement with the short slats; which must first be passed between the two wires forming the marginal cable strand before the twisting of such wires in the reverse directions, best seen in Figure 13. The placement of the long and short slats between all of the pairs of wires forming the several cable strands, with the exception of the top marginal cable strand, provides the retention means whereby the alternate reverse twisted portions may be accomplished as a result of the reverse rotations of the twisters and for securing the long and short slats to said wires. This

same result is obtained in the placement of the upper ends of the long slats between the pairs of wires forming the top marginal cable, but some retention means must be provided for these wires forming the top marginal cable strand at points mediate the long slats whereby to produce the reverse twisting action in such marginal cable and by the means provided for accomplishing this result, the reverse twisted portions of the cable strand between the upper ends of the long slats are naturally much longer than such twisted portions appear in the other cable strands and particularly those engaging and securing the alternate long and short slats or wood pickets. To accomplish this twisting of the wires forming the top cable strand, after the feeding and placement of the short slats or wood pickets, there is provided a reciprocately supported retention member 42, the upper end of which has a wire receiving slot or throat 43. This member is not only supported whereby it may have reciprocal movement, but is capable of oscillatory movement whereby it may adapt itself to the longitudinal movement of the cable strand resulting from the feeding operations imparted to such cable strand, or pulling out thereof, during the wrapping operation of the completed fence or fabric.

Reference being had to Figures 4, 7 and 8, the operation and function of this retention member is very clearly set forth. It will be observed that the retention member assumes a preferably vertical position having a pivotal connection at its lower end with a lever bar 44 and extending up therefrom passes through a slotted frame 45, which not only guides the retention member during its reciprocal movement, but also permits the oscillatory movement referred to from the fulcrum point where it is pivoted to the lever bar 44. This lever bar has a pivotal connection at 46 with the machine frame and on one end carries a roller 47 which is adapted to ride on a cam member 48 secured to the operating shaft 4. The other end of the lever bar 44 is curved upwardly, as at 49, and between this curved portion of said lever bar and the retention member 42, there is a connecting rod 50 on which and between the retention member and said lever bar is carried a spring 51 and connecting the body portion of said lever bar and extending therefrom to a frame part 52 is a rod 53 on which and between the lever bar and the frame portion 52 is carried a spring 54. The timing of the cam 48 is such that instantly after the placement of the short slats or wood pickets, the lever bar 44 is actuated to project the retention member 42 in an upward direction, causing the wires comprising the marginal cable strand to become seated in the slotted

or throated portion 43 in the upper end of said retention member, as best seen in dotted lines in Figure 10, and also in full lines in Figure 11, which makes it possible to 5 complete the reverse twist in the top marginal strand at a point mediate the long slats or wood pickets, as shown in Figures 11 and 13. During this twisting operation to produce the reverse twisted portions in 10 the marginal cable strand between the long slats, the fabric is moving forward and it is obvious that the upper end of the retention member 42 must move forward therewith a sufficient distance to allow for the 15 completion of the reverse twisting operation of the top marginal cable strand. Such movement is permitted by reason of the pivotal connection between the retention member 42 and the lever bar 44, the movement 20 being somewhat as illustrated by the full and dotted line positions of the retention member 42, as best seen in Figures 7 and 11. On the completion of this reverse twisting operation, the cam 48 has moved 25 to a position to permit the lowering of the retention member 42 and its disconnection with the marginal cable strand. This withdrawal of the retention member 42 from engagement with the top marginal strand, 30 is accomplished through the action of the cam and the spring 51 which has been compressed during the oscillatory movement of said retention member by reason of the feeding or pulling out of the fabric, then acts 35 to return the retention member to its initial vertical operating position. During the withdrawal movement of the retention member 42 to return it to its initial position will result in compressing the spring 54 which 40 acts in timed relation to the position assumed by the cam 48 to cause the retention member 42 to be again projected vertically to engage the wires forming the top marginal strand immediately upon the placement of the next and succeeding alternate short slat or wood picket. Such operations as I have described are continued periodically and from time to time with the feeding and placing of each alternate short 45 slat or wood picket.

The packer mechanism for moving the slats or wood pickets sidewise and into the crotches formed by the twisting of the wires comprising the cable strands, which, as will 50 be understood, is after the feeding of said slats or wood pickets by the starting and feeding rollers, comprises a transversely disposed and movably supported bar 55 to which are connected blocks 56 supporting 55 transversely arranged sectional angle bars 57 which, as best seen in Figure 1, are normally located between the twister heads 24. In the initial feeding of the slats or wood pickets they are passed through the 60 twister heads and supported upon these

angle iron sections 57, as will be seen in dotted lines in Figure 9. To the opposite ends of the bar 55 are connected reciprocally supported rods 58 guided in their movements by and through frame parts 59. The 70 opposite ends of these bars 58 are connected by links 60 to the upper ends of lever bars 61 which are pivoted at 62 to castings 63 secured to the frame of the machine, the lower ends of said lever bars having connected thereto rods 63 which pass through frame parts and carry springs 64. The lever bars 61 also have connected thereto rollers 65 adapted to ride on cams 66 secured to the shaft 4. These cams 66 are timed in 75 their operation to move the supporting bar 55 forward immediately upon the feeding and placement of a slat or wood picket on the angle sections 57 to be deposited in the crotches of the wires forming the cable strands, whereby during the reverse twisting operation of said cable strands the slats or wood pickets may be secured in proper position thereto. In Figure 9 the supporting bar 55 is shown in slat receiving position in full lines and in slat deposited and wire securing position in dotted lines. During the operation of the cams 66 to move the supporting bar 55 forward, the spring 80 85 90 95 100 105 110 115 120 125 130 64 is compressed and immediately upon the cams 66 being rotated to position to permit the withdrawal or return of said supporting bar 55 to its initial position, the springs 64 function to accomplish this purpose.

The fabric as it is completed passes over a tension roller D and down and around a pulling out roller E and thence to a wrapper F on which the completed fabric is wound. The tension roller acts as an idler and is not driven, but the pull out E has a shaft e' to which is connected a sprocket wheel e² driven by a sprocket chain e³ engaged by a sprocket pinion e⁴ on a shaft G, which also has connected thereto a gear wheel g and a sprocket wheel g'. The gear wheel g receives its power from the operating shaft 4 and from a gear pinion g² thereon which meshes with a gear pinion g³ which in turn meshes with the gear wheel g.

Power is supplied to the machine from any suitable source, preferably through a belt, not shown, which is adapted to drive the pulley H loosely carried on the driving shaft 1, but adapted to be clutched thereto by the friction clutch h movable into and out of operative engagement by means of the hand operated lever h'. The small gear pinion 17, previously referred to, is preferably loose on the shaft 1, but adapted to be clutch connected thereto by means of the clutch member I, to which is operably connected the hand lever i. With these power connections, when the clutch I is connected to the gear pinion 17 and the pulley H is in driving connection with the driving shaft 1,

power may be imparted from the shaft 1 to the various operating shafts and various operating parts which act in timed relation to receive a slat, start it into feeding position, feed it to the twisters and through the operation of the latter, twist the wires forming the cable strands by reverse twists to secure the slats or wood pickets thereto and thereby completes the fence fabric which is wound into rolls on the wrapper F. The operator, through the lever h', may disconnect the machine from the source of power by the disconnection of the clutch h from the pulley H, or such power connection may remain intact and he may, by the operation of the lever i, disconnect the gear wheel 16 from the driving shaft 1, which will immediately stop the operation of the twisters.

While the wire guiding means for the wires from the reels, not shown, to the twisting spindles, is immaterial, as they are well known and in general use, I have shown a frame J on which is journaled a shaft j provided with grooved wire guiding rollers or wheels j', around which the wires comprising the cable strands are directed to the coiling spindles or shafts.

The speed ratio between the spindle for the top marginal cable strand and the remaining spindles should be maintained approximately two to one, for the reason that the wires forming the top marginal strand between the longer slats must be intertwisted by reverse twists substantially throughout between said long slats; whereas, where the short slats are positioned between the long slats the wires securing the same are twisted only the distance between the adjacent long and short slats.

40. What I claim is:—

1. In a fence machine, twisters for twisting cable strands to secure alternate long and short wood slats, means to rotate the twisters, means to rotate the marginal twister for the top marginal cable strand at an increased speed over the remaining twisters, and retention means to engage the top marginal cable strand between the upper ends of the longer slats to accomplish the twisting of such strand at the same time as the securing of a short slat to the other strand.

2. In a fence machine, twisters for twisting cable strands to secure long and short wood slats, means to alternately rotate said twisters in opposite directions to twist said strands first in one direction and then in an opposite direction, means to rotate the marginal twister for the top marginal cable strand at an increased speed over the remaining twisters, and retention means to engage the top cable strand between the upper ends of the longer slats during the interval of securing a short slat to the other strands, whereby the reverse twisting of the top

marginal cable may be accomplished between the longer slats.

3. In a fence machine, twisters for twisting cable strands to secure thereto and therein long and short wood slats, means to alternately feed long and short slats between the wires forming each cable strand and to place the short slats for securing by all strands except the top marginal strand, and retention means adapted to engage the top marginal strand following the placement of each short slat, whereby the twisting of said marginal strand may be accomplished while the short slats are being secured to the other strands.

4. In a fence machine, twisters for twisting cable strands to secure thereto and therein long and short wood slats, means to rotate said twisters first in one direction and then in an opposite direction, means to rotate the top marginal twister at a speed greater than the remaining twisters but all in timed relation so as to receive said slats as fed, means to alternately feed long and short slats between the wires forming each cable strand and to place the short slats for securing by all strands except the top marginal strand, and retention means adapted to engage the top marginal strand following the placement of each short slat, whereby the twisting of said marginal strand may be accomplished while the short slats are being secured to the other strands.

5. In a fence machine, twisters for twisting pairs of wires to form cable strands, means to rotate said twisters first in one direction and then in an opposite direction, means to alternately feed long and short wood slats through and between the wires forming each cable strand and to place the short slats for securing by all strands except the top marginal strand, a packer means to move each slat sidewise and longitudinally of and between the wires for securing the same, and a retention means to engage the top marginal cable strand at the point made vacant by each short slat and in axial alignment therewith, whereby said marginal strand may be twisted in reverse directions between the long slats while the short slats are secured to the other wires.

6. In a fence machine, twisters for twisting pairs of wires to form cable strands, means to rotate said twisters first in one direction then in an opposite direction, means to feed said wires continuously, means to alternately feed long and short wood slats crosswise between each pair of wires, the short slats being of a length for securing to all strands except the top marginal strand, a packer mechanism for placing each slat when fed into proper position between its pairs of wires to allow for the proper reverse twisting of such wires, and a retention means to engage the top marginal strand

between long slats at a point made vacant by the short slats and in axial alignment therewith, whereby said marginal strand may be twisted in reverse directions between the long slats while the short slats are secured to the other wires, said retention means capable of being moved into and out of engagement with said marginal strand while the latter is moving and to be moved therewith a predetermined distance.

7. In a fence machine, twisters for twisting pairs of wires to form cable strands, means to rotate said twisters first in one direction then in an opposite direction, means to alternately place a long wood slat across and between the wires forming each cable strand and a short slat between each long slat to be secured by all but the top marginal strand, a retention means to engage 15 the top marginal strand at the point made vacant by each short slat, said retention means comprising a reciprocally supported bar capable of limited oscillatory movement, and means to actuate said retention bar.

20 8. In a wood slat fence making machine, in combination with slat feeding and wire twisting means, of wire retention means comprising a member movable to engage and release such wire between the feeding of certain slats, and means to alternately move 25 said member into and out of operative position with said wire.

9. In a wood slat fence making machine, in combination with slat feeding and wire twisting means, of wire retention means comprising a reciprocal member movable to engage and release such wire between the feeding of certain slats, a lever means to reciprocate said member, and means to operate 30 said lever means.

40 10. In a wood slat fence making machine, in combination with slat feeding and wire twisting means, of wire retention means comprising a reciprocal member provided with a wire seat and movable to engage and release such wire between the feeding of certain slats, a lever bar for moving said member, a cam means to move said lever bar in one direction and spring means to move said lever bar in the opposite direction.

45 11. In a wood slat fence making machine, means for continuously feeding forward pairs of strand wires, means for feeding wood slats across and between said pairs of wires, means for alternately twisting each pair of wires first in one direction then in an opposite direction, one such twisting means adapted to impart longer reverse twists of pairs of wires than are imparted to the other pairs of wires, a retention member movable to engage and disengage with such wires having such longer reverse twists and to move a predetermined distance there- 55 with when engaging the same, a lever bar

for operating said member to move it into operative and inoperative positions, a cam means to move said lever bar in one direction, spring means to move said lever bar in the opposite direction, and spring means to return said member after moving a predetermined distance with said wires.

5 12. The wire retention means herein described, comprising a vertically movable and oscillatory bar provided with a wire 75 seat, a lever having a pivotal connection with said bar, an operating shaft, a cam on said shaft for actuating said lever, spring means for moving said bar vertically in one direction, and spring means for oscillating 80 said bar in one direction of its movement.

13. The packer mechanism herein described, comprising a movable bar supporting sectional guides for wood slats, an operating shaft, cams on said shaft, a pair of 85 levers, each operated in one direction of movement by said cams, spring means to move said levers in opposite directions, and connections between said levers and said movable bar.

90 14. In a fence machine, a plurality of twister spindles, a twister on each spindle, a rack bar for rotating said twister spindles in opposite directions, a driving shaft, an operating shaft adapted to be clutch connected with said driving shaft, a lever member operatively connected with said rack bar, a frame member pivotally connected with said lever and movable transversely across said operating shaft, an eccentric member 100 on said operating shaft within said frame member, and a pair of rollers journaled in said frame member and adapted to be alternately engaged by said eccentric member for reciprocating said frame member. 105

15. In a fence machine, a plurality of twister spindles, a twister on each spindle, a reciprocal rack bar, gearing between said rack bar and certain of said spindles for rotating said spindle at uniform speed, gearing between said rack bar and one of said spindles for rotating such spindle at a speed differing from the other spindles, a driving shaft, an operating shaft adapted to be clutch connected with said driving shaft, a lever 110 member operatively connected with said rack bar, a frame member pivotally connected with said lever and movable transversely across said operating shaft, an eccentric member on said operating shaft within said 115 frame member, and a pair of rollers journaled in said frame member and adapted to be alternately engaged by said eccentric member for reciprocating said frame member.

16. In a fence machine, twisters for twisting alternate twists in pairs of wires to form cable strands, means for feeding wood slats transversely of and between said pairs of wires and alternately to the twisting of 120 125 130

said pairs of wires, the alternate slats being short slats and being secured to all but the top cable strand, and means operable on the placement of said short slats to engage the top marginal strand at the points left vacant by said short slats and in axial alignment therewith, whereby connected al-

ternate twists are formed in said top cable strand and between the longer slats and of a length longer than the twists in the other wires between the long and short slats.

In witness whereof I have hereunto set my hand this 10th day of December, 1926.

DOUGLAS A. WILSON.
